Filed July 24, 1963, Ser. No. 297,294

9 Claims. (Cl. 66—163)

This invention pertains to slub catchers for use in circular multi-feed knitting machines and more particularly to apparatus for detecting and catching yarn slubs which appear during feeding of the yarn through apparatus such as rib or plain large diameter body fabric knitting machines.

Low grade yarns of cotton or other fibers sometimes contain what are known as slubs. These are thick, bulky enlargements of the yarn composed of lumps of loose fibers collected on the yarns at the time of spinning or twisting. Although both spinning and twisting machines are generally equipped with devices known as slub catchers to detect such defects, one or more slubs may occasionally be accidentally missed and wound with the yarn forming the finished package.

When yarns having slubs are used in knitting rib or plain fabric on circular machines of either the rotary or the stationary needle bed type, there is the possibility that a slab on the yarn will be drawn into the needles of the machine. If the slab is sufficiently large it may damage the needles. If the aperture in a guide or feed finger through which the yarn passes is small enough to prevent passage of the slab, the yarn will be severed by the needles. The fabric thereupon will drop from the machine. An undetected slab may be expected therefore to result in a defect in the fabric causing considerable expense and increased cost due to loss of production, unmarketable fabric and possible machine damage.

Knitting machines are equipped with stop motions designed to stop the machine if yarn breaks. On the other hand, the stop motions heretofore available generally will not detect a slab.

Slab catchers are available to the knitting industry which are combined as units with stop-motion detectors and are designed to be mounted above the yarn supply packages on the knitting machines. These units are rather bulky, and, together with the necessary electrical conductors, seriously interfere with access to the yarn packages. Ready access to the yarn packages is essential when changing or renewing the same.

An additional and significant problem arises in the use of circular body fabric machines having rotating dials and/or overhead yarn supply racks. Sudden stopping of such large diameter multi-feed machines must ordinarily be avoided because of the weight of the revolving parts. Such machines must normally be brought to a coasting stop in as brief a time interval as possible. This is necessary because knitting continues until the machines have completely decelerated and yarn must be made available to the needles during the entire period of deceleration to prevent breaking of the yarn.

A commercially satisfactory solution to the problems recited above is needed. The present invention provides just such a solution. A slab catcher is so designed and located in relation to a yarn package, stop-motion slab detector and yarn guide apparatus that when a slab is detected and caught, conventional overhead stop-motion apparatus immediately initiates the usual automatic sequence of events that stop the machine and at the same time causes provision of sufficient length of free yarn to supply the needles until the machine comes to a complete stop, without the slab having been passed on to the needles.

While, generally only one yarn and the elements associated therewith will be shown and described, it is to be understood that a similar arrangement can be provided for each yarn on a multi-feed machine.

5 Those elements of a knitting machine which are not necessary to a comprehensive and workable presentation of the invention have been omitted from the drawings in order that the nature of the invention will readily become apparent.

10 In the drawings—

FIGURE 1 is a plan view of a multi-feed circular body fabric knitting machine showing the yarn packages, slab catchers, stop-motion slab detectors and yarn guide apparatus used in the invention.

15 FIGURE 2 is a view in elevation of the multi-feed knitting machine of FIG. 1 showing just two feeds, in order to maintain clarity. Each feed is illustrated as if in normal operation, no slab being present. In addition, the figure illustrates a drive unit connected to a 20 stop motion slab detector.

25 FIGURE 3 is a detail view in side elevation of one of the slab catchers used in the invention, showing a slab preventing yarn from moving along the normal path through the slab catcher. The figure also shows in dotted position the slab drawn from the slab catcher and the yarn thus bypassing the latter.

30 FIGURE 4 is a view in elevation of the novel slab catcher as seen looking radially outward from the center of the knitting machine.

35 FIGURE 5 is a view in perspective of one of the novel slab catchers, and detectors and yarn guide apparatus associated therewith, illustrating how, when a slab is caught, the yarn is tightened to actuate the associated yarn guide and stop-motion slab detector, the yarn thereafter assuming a shorter than normal path of traverse.

40 FIGURE 6 is a view in elevation of the knitting machine of FIGURE 2 just after a slab has been caught, and the associated yarn guide and stop-motion slab detector has been actuated by the yarn loop.

45 FIGURE 7 is a view in elevation of the knitting machine of FIGURE 6 showing after the slab has been disengaged in such manner from the slab catcher how enough yarn can be drawn from the yarn package over the new and short route to the needles until the machine comes to a stop, without the slab being passed onto the needles.

50 In FIGURE 2 of the drawings the knitting head of a multi-feed circular body fabric knitting machine is indicated generally by the arrow 2. Outside the head are a plurality of pillars 4 which support cross-bars 6 (FIGS. 1, 2 and 7). On the head per se, cylinder needle cams and dial needle cams are indicated by 43 and 44 respectively.

55 The conventional central vertical support rod 8 for the yarn is supported on the cross-bars 6 as usual. Just above the cross-bars 6 are the conventional hub 10 and support arms 22 carrying the yarn support bases or supply stands 20 for the yarn packages 18. Still on the central support rod 8, but above the yarn supply stands, is a yarn guide disc 12 having eyes 13 therearound, the yarns passing 60 downwardly through these eyes to the knitting head of the machine. Just above the disc 12 is a hub 14 with outrigger support arms 26 going to the individual novel slab catchers, indicated generally by the arrow 24, of the present invention, and above the slab catcher support hub 14, still on the central rod 8, is a spider 16 with legs 29 radiating therefrom carrying the stop-motion slab detectors shown generally by the arrow 28.

65 The yarns going downward to the yarn guide disc come from the individual pivoted yarn guides 30 which act as stop-motion slab detector arms or triggers and these are either electrically (as shown by wires 45) or mechanically

connected to a trip mechanism or brake 47 to stop the machine if any one of the detector arms is pulled downward to the position shown by the upper right hand yarn guide and detector arm shown in FIGURE 6. Thus if the yarn riding on a detector arm is tensioned by a slub, as hereinafter described, the drive 46 of the machine is cut off and the brake 47 is so applied as to bring it to a coasting stop.

Turning now to the slub catcher 24 itself, this unit has a vertical post 32 adjustably clamped by a screw 34 to the outrigger support arm 26. At the lower end of the vertical post is a plate 37 for a yarn guide device or eye 38 which plate and eye are attached to the under side of the slub catcher at the lower end of the vertical post by a screw 36 (see FIG. 3). The yarn 19 coming from the yarn package 18 passes through the eye 38 from below. This is true whichever of the two positions shown in FIG. 3 the yarn occupies as it leaves the upper side of the eye. Above the support arm 26 a pair of blades 40 is carried on the post 32. The blades slope downward toward the center of the machine (see FIGURES 3, 4, 5 and 6). Each blade is adjustably mounted by means of a separate over-sized hole and a screw 42. The facing edges of the blades are preferably substantially parallel to each other and are set to provide an opening or gap 41 just wide enough to permit the yarn to pass freely therethrough but to catch and prevent passage therethrough of any slub that may come along.

When the yarn coming from the yarn package 18 is normally threaded up it will pass through the yarn guide eye 38, between the blades 40, and up to the pivoted yarn guide and stop motion slub detector arm 30.

For clarity of description the portion of the yarn between the slub catcher 24 and the pivoted yarn guide and detector arm or trigger 30 is identified in the drawings by the reference character 21. The portion of the yarn passing downward from the detector arm 30 to the centrally disposed yarn guide device or eye 13 is identified by the reference character 23. From the said eye 13 the yarn passes downward to the usual yarn guide 15 and finally to the needles indicated generally at 17 (see FIG. 2). This arrangement is true whether the machine has only cylinder needles or is a rib machine with dial needles as well. The machine shown in FIGS. 2 and 7 is a rib machine.

Having thus set forth the arrangement of parts of the machine so far as is necessary to ensure understanding of the invention, I shall now describe the operation of the machine.

During knitting the yarn is normally drawn along the path recited above, which is the path shown on the left and right sides of FIG. 2. If a slub 27 comes from the yarn package 18 it will pass through the eye 38 just under the slub catcher outrigger support arm 26 and be caught by the blades 40 of the slub catcher itself. This activity immediately results in abnormal tensioning of the yarn portions 21 and 23 going to and coming from the detector arm or trigger 30, and the said yarn pulls the arm 30 downward to the position shown on the right of FIGURES 5 and 6. This pivotal action of the arm 30 acting through the rest of the stop motion apparatus, including the drive 46 and the brake 47, cuts off the current and initiates a coasting of the machine to a stop. The pivotal movement of the detector arm 30 also releases that loop of yarn formed by the portions 21 and 23 thereof which met in contact with the arm 30, so that the loop falls free. It will be noted that up to this moment the yarn has been passing upward for some distance from the slub catcher 24 to the detector arm 30 as shown by the yarn portion 21 and downward again to a position slightly below the slub catcher at the eye 13 as shown by the yarn portion 23. These two yarn portions and part of the portion 19 from the eye 13 to the needles all precede the slub 27 and are on the needle side thereof. The release of the portions 21 and 23 makes it possible for the machine to continue to knit for a short time while it begins to slow down, 75

by drawing on the yarn portions 21 and 23 until the yarn assumes a shorter path 25 defined by the yarn passing directly from the slub catcher to the eye 13. Thereafter, and in addition, as can be seen from the dotted position of the yarn in FIGURE 3, not only does this change of path of traverse provide considerable yarn which can be knit while the machine slows down but as the portions 21 and 23 are drawn down the slub 27 is easily, and without force, freed from the slub catcher and the portion of yarn 25 is thereafter enabled to move in the direction of the knitting head 2 with no interference until the slub 27 reaches the yarn guide 15 (see FIG. 7). This arrangement creates, in effect, two yarn supplies which together generate a quite adequate quantity of yarn that enables the machine to come to a complete stop before the slub comes up against the yarn guide 15.

An additional path of yarn traverse is provided by the invention. Relative to each other, there is a first and normal longer-than-necessary path that includes the slub catcher 24 and the yarn guide and stop-motion slub detector arm or trigger 30, and a second path substantially shorter than the first, which second path bypasses the two aforesaid elements and is used during the deceleration of the knitting machine. The shift from the longer-than-necessary path to the second and short path results in the generation of a length of free yarn but which generally would be insufficient were it not for the disengagement of the arrested slub from the slub catcher in such a manner that yarn can again be drawn from the yarn package until the slub reaches the yarn guide 15. However, before this can occur the machine has come to a complete stop.

The location and mounting of the various elements used in the invention are important to achievement and workability of the invention. The disclosed system provides means for detecting and catching slubs, actuating stop motions and thereafter ensuring availability of a supply of free yarn which is sufficient to continue the knitting operation until the machine has completely stopped. Passage of any slub to the needles is positively prevented. Yarn remains unbroken. Damage to the machinery is prevented. Fabric remains in place. To resume knitting by the machine, an attendant has only to pick off any offending slub, reset the yarn guide and detector arm, rethread the slub catcher, pass the yarn over the arm and start the machine.

It is to be understood that the embodiments of this invention as described above and in the claims that follow, are not intended to limit the scope of the invention thereto. Modifications not here suggested, which may occur to those normally skilled in the art are also considered to be within the ambit of the invention.

What is claimed is:

1. A multi-feed circular knitting machine having
  - (a) a knitting head,
  - (b) a stop motion adapted to bring the machine to a halt,
  - (c) a yarn supply for each feed,
  - (d) a separate catcher for slubs coming from the yarn supply associated with at least one feed and located above the knitting head, in combination with
  - (e) a slub detector in each feed having a catcher, located above the catcher and remote therefrom, adapted when the catcher engages a slub and thus tensions the yarn to trigger the stop motion and release the yarn from the slub detector,
  - (f) a yarn guide device for each catcher near the level thereof but laterally separated therefrom and adapted to receive yarn from the associated slub detector, there being
  - (g) open end blades on each catcher so disposed in relation to each other as to provide space therebetween sufficient for the yarn to pass to the slub detector and narrow enough to catch a slub, subsequent triggering of the stop motion by the slub detector ini-

tiating a change of the angle of traverse of the yarn relative to the catcher and generation of surplus free yarn between catcher and yarn guide device for knitting and simultaneously causing the slab to freely slip out from the open ends of the blades and feed toward the needles;

whereby two supplies of yarn are obtained to feed the needle while the machine decelerates, without breaking the yarn and causing damage to the fabric.

2. A multi-feed circular knitting machine having
 (a) a stop motion adapted to bring the machine to a halt,
 (b) a yarn supply for each feed, and
 (c) a separate catcher in each feed for slubs coming from the yarn supply associated with that feed, in combination with

- (d) a slab detector in each feed mounted above each catcher and remote therefrom to receive yarn from the catcher, adapted when the catcher engages a slab and tensions the yarn to trigger the stop motion and release the yarn from the slab detector, and
 (e) a yarn guide device for each catcher near the level thereof but laterally separated therefrom adapted to change the angle of traverse of, and receive yarn from the associated slab detector and freely guide the slab away from the catcher;

whereby when a slab is engaged by a catcher those portions of the yarn from the catcher to the detector and from the detector to the guide device are shortened to a single portion moving directly from adjacent catcher to guide device, thereby supplying slab-free yarn to the knitting operation while the machine is slowing down.

3. A multi-feed circular knitting machine having
 (a) a stop motion adapted to bring the machine to a halt,
 (b) a yarn supply for each feed and
 (c) a separate catcher in at least one feed for slubs coming from the yarn supply associated with that feed,

- (d) said catchers each being above the knitting head and having two open-end blades with sufficient space for the yarn to pass therebetween and narrow enough to catch a slab, in combination with
 (e) a slab detector above each catcher adapted to receive the yarn from the catcher and to trigger the stop motion and initiate a change of the angle of traverse of the yarn relative to the catcher to permit the slab to freely slip out of the open ends of the blades and feed toward the needles;

whereby the portion of the yarn containing the slab and held by the catcher can be fed toward the needles while the machine is stopping, without damage to the fabric.

4. A multi-feed circular body fabric knitting machine having
 (a) a knitting head,
 (b) a stop motion adapted to bring the machine to a halt, and
 (c) a yarn package for each feed, in combination with
 (d) separate means to protect the fabric from damage due to slubs from each yarn package comprising
 (e) a slab catcher mounted above the knitting head,
 (f) a slab detector mounted above the slab catcher and adapted to trigger the stop motion and release the yarn from the slab detector when the slab catcher engages a slab and tensions the yarn,

- (g) a yarn guide device disposed near the level of but laterally separate from the slab catcher and adapted to receive yarn from the slab detector initially and from adjacent the slab catcher after the slab detector has released the yarn, said catcher comprising two blades sloping downward toward the center of the

machine and open at their lower ends, there being space between the blades sufficient to pass the yarn therethrough and narrow enough to catch a slab, the elevation of the guide device being such that when the yarn goes direct from the slab unobstructedly catcher to the said device the slab slips out the open ends of the blades and can feed toward the needles while the machine slows down.

5. A multi-feed circular body fabric knitting machine having

- (a) a knitting head,
 (b) a stop motion,
 (c) a yarn package for each feed, and
 (d) braking means adapted to bring the machine to a coasting stop after detection of a slab, in combination with
 (e) separate means for each yarn package to protect the fabric from damage due to slubs comprising a slab catcher sloping downward at an angle to the horizontal toward the center of the machine and mounted above the knitting head, said catcher having two blades with open lower ends with space therebetween sufficient to pass the yarn and narrow enough to catch a slab,
 (f) a slab detector coordinated with the stop motion and located above the slab catcher, at an angle in relation therewith, to receive yarn from the space between the blades, said detector being adapted to trigger the stop motion when the slab catcher engages a slab and thereby tensions the yarn, and
 (g) a centrally disposed guide eye just beneath the slab catcher to ensure that after triggering of the stop motion any yarn going direct from adjacent the slab catcher to the yarn guide eye readily slides out from under the open ends of the blades and moves toward the needles while the machine slows down.

6. A multi-feed circular body fabric machine having

- (a) a knitting head, and
 (b) a yarn package for each feed located above the knitting head, said knitting head having therein
 (c) independent needles,
 (d) body means in the head to carry the needles, and
 (e) yarn guides to deliver yarn from the yarn packages to the needles, there being relative rotary movement between the body means and the guides, and in combination with the knitting head

- (f) a stop motion slab detector for each feed,
 (g) braking means adapted to bring the machine to a coasting stop upon detection of a slab,
 (h) a separate slab catcher for at least one feed above the knitting head but below the associated slab detector, said catcher having two blades at an angle to the horizontal facing downward toward the center of the machine, the blades having open lower ends with space therebetween sufficient to pass the yarn and narrow enough to catch a slab, the associated slab detector being adapted to trigger the stop motion when the slab catcher engages a slab thereby tensioning the yarn, and

- (i) a yarn guide eye disposed near the level of but laterally separate from the slab catcher and adapted to receive yarn from the associated slab detector initially and from adjacent the slab catcher after the associated slab detector has released the yarn, the elevation of the guide eye being such that when the yarn goes direct from adjacent the slab catcher to the said eye the slab easily slips out the open ends of the blades and can feed toward the needles while the machine slows down.

7. A multi-feed circular body fabric machine having

- (a) a knitting head and
 (b) a yarn package for each feed located above the knitting head, said knitting head having therein
 (c) independent needles,
 (d) a needle cylinder containing needles and

- (e) a dial containing needles, and
  - (f) yarn guides to deliver yarn from the yarn packages to the needles, there being relative rotary movement between the cylinder and dial on the one hand and the yarn guides on the other, and in combination with the knitting head
  - (g) a stop motion slub detector for each feed,
  - (h) braking means adapted to bring the machine to a coasting stop upon detection of a slub,
  - (i) a separate slub catcher for each feed above the knitting head but below the associated slub detector, each such catcher having two blades at an angle to the horizontal facing downward toward the center of the machine, the blades having open lower ends with space therebetween sufficient to pass the yarn and narrow enough to catch a slub, the associated slub detector being adapted to trigger the stop motion when the slub catcher engages a slub thereby tensioning the yarn, and
  - (j) a yarn guide eye disposed near the level of but laterally separate from the slub catcher and adapted to receive yarn from the associated slub detector initially and from adjacent the slub catcher after the associated slub detector has released the yarn, the elevation of the yarn guide eye being such that when the yarn goes direct from adjacent the slub catcher to the said eye the slub slips readily out the open ends of the blades and can feed toward the needles while the machine slows down.
8. A multi-feed circular body fabric machine having
- (a) a knitting head,
  - (b) a yarn package for each feed located above the knitting head,
  - (c) independent latch needles in the head,
  - (d) a stop motion slub detector for each feed and
  - (e) braking means adapted to bring the machine to a coasting stop upon detection of a slub, in combination with
  - (f) a slub catcher for each yarn package located above the knitting head,
  - (g) said catcher having two blades at an angle and having open ends with space between the blades sufficient to pass the yarn onto the associated slub detector and narrow enough to engage any slub thereby tensioning the yarn, the associated slub detector having a trigger pivoted to release the yarn when actuated by such tension, and
  - (h) a disc with a guide eye for each catcher near the level of the latter but centrally located on the machine and laterally separated from the catcher adapted to receive yarn from the associated slub detector until a slub is detected,
  - (i) the angle of the blades being from the horizontal downward toward the center of the machine and the level of the disc being such that the dropping of the yarn by the pivoting of the trigger both shortens the path of the yarn from adjacent the catcher to the disc and allows the slub to easily slip out the open ends of the blades;

whereby there is surplus yarn which has passed the catcher and thereafter yarn following the slub both of which surpluses can feed toward the needles while the machine is slowing down.

9. A multi-feed circular body fabric machine having
- (a) a knitting head,
  - (b) a yarn package for each feed located above the knitting head,
  - (c) cylinder needle cams and dial needle cams in the knitting head,
  - (d) independent latch needles in the head,
  - (e) a plurality of pillars extending upwardly past the head,
  - (f) cross-bars above the head supported by the pillars,
  - (g) a vertical rod at the center of the machine carried by the cross-bars, and
  - (h) a support for each yarn package, mounted on the central rod but radially spaced therefrom, in combination with
  - (i) a stop motion slub detector for each package having a pivoted trigger,
  - (j) braking means adapted to bring the machine to a coasting stop upon detection of a slub,
  - (k) a slub catcher for and just above each yarn package radially spaced from the central rod having two blades facing downward at an angle toward the central rod with space therebetween sufficient to pass the yarn and narrow enough to engage a slub, the associated slub detector receiving yarn from the downward angled blades and upon engagement of a slub by the catcher adapted to be triggered by the resulting yarn tension and to drop the yarn by pivoting the trigger of the associated slub detector, the lower ends of the blades being open, and
  - (l) a yarn guide disc on the central rod with guide eyes therein for the yarn, there being relative rotation between the cylinder and dial on the one hand, and the disc on the other, the disc being located close to the rod at such level that the dropping of the yarn by the pivoting of the trigger shortens the yarn path to the knitting head thereby supplying surplus slub free yarn usable while the machine coasts to a stop, and also lowering the yarn from the catcher to a position below the open ends of the blades thus readily freeing the slub and allowing the yarn following the slub to move toward the needles as a second source of yarn supply the machine slows down.
